United States Patent Office.

GEORGE H. GRANT, OF RICHMOND, INDIANA.

Design No. 4,845, dated April 25, 1871.

DESIGN FOR THE ENDS OF SCHOOL-DESKS AND SEATS.

The Schedule referred to in these Letters Patent and making part of the same.

I, GEORGE H. GRANT, of Richmond, in the county of Wayne and State of Indiana, have invented and produced a new and original Design for School-Furniture, of which the following is a specification.

The nature of my invention will appear by reference to the accompanying photographic illustration, in which—

Figure 1 is a view of one of the standards or side frames of a combined school-desk and seat.

Figure 2 is a view of the reverse side of the corresponding standard with the removable pieces detached.

A represents the standard;

B, the seat-brackets;

C, the bolt for pivoting the seat-brackets to the standards;

D, the supporting flange for the desk;

E, the supporting flange for the book-shelf; and

F, a tongue or tenon for bracing the seat-back and standards.

As shown in fig. 1, the head of bolt C forms the center of the rosette of the joint-piece of the seat-bracket and standard.

The main uprights of the standards are ornamented with leaf-work. The upper portion, which supports the desk and book-shelf, is made to represent branched rustic-work, and the lower part of the standard is formed into two legs, curving in opposite directions, and united by a brace or cross-bar.

The accompanying illustration renders further or more particular description of my design unnecessary.

What I claim as my invention is—

The design for school-furniture, as shown and described.

GEO. H. GRANT.
